Primary Examiner — Darlington Ly

(57) **CLAIM**

The ornamental design for a motorcycle, as shown and described.

DESCRIPTION

1. Motorcycle

1.1 is a front and right side perspective view of a motorcycle embodying our new design;
1.2 is a left side elevation view thereof;
1.3 is a right side elevation view thereof;
1.4 is a top plan view thereof;
1.5 is a front elevation view thereof;
1.6 is a rear elevation view thereof;
1.7 is a front and left side perspective view thereof; and
1.8 is a bottom plan view thereof.

The broken lines in the drawings illustrate portions of the motorcycle that form no part of the claimed design.

1 Claim, 8 Drawing Sheets
